HANDKERCHIEF OR SIMILAR ARTICLE

Mabel A. Norris, Durango, Colo.

Application October 15, 1953, Serial No. 27,190

Term of patent 7 years

(Cl. D3—12)

To all whom it may concern:

Be it known that I, Mabel A. Norris, a citizen of the United States, residing at Durango, in the county of La Plata and State of Colorado, have invented a certain new, original, and ornamental Design for a Handkerchief or Similar Article, of which the following is a specification, reference being had to the accompanying drawing, forming part thereof.

In the drawing:

The figure is a plan view of a handkerchief or similar article showing my new design.

I claim:

The ornamental design for a handkerchief or similar article, substantially as shown.
